(57) **CLAIM**

The ornamental design for a handrail assembly for mounting to a portable tank, as shown and described.

DESCRIPTION

FIG. 1 is a rear, right side, elevated perspective view of a handrail assembly for mounting to a portable tank of the present invention, the handrail assembly being in a folded position.

FIG. 2 is a front elevation view of the handrail assembly. FIG. 3 is a left side elevation view of the handrail assembly. The right side elevation view is a mirror image of the left side elevation view.

FIG. 4 is a top plan view of the handrail assembly.

FIG. 5 is a bottom plan view of the handrail assembly.

FIG. 6 is a rear elevation view of the handrail assembly; and, FIG. 7 is a left side elevation view of the handrail assembly showing it mounted to the portable tank.

Dashed or dotted lines represent the operating environment and form no part of the claimed design. The shade lines in the figures show contour or flatness and not surface ornamentation.
